UNITED STATES PATENT OFFICE.

MARTIN WILLIAM LINDGREN, OF CHICAGO, ILLINOIS.

INTERNAL-COMBUSTION ENGINE.

Application filed July 14, 1924. Serial No. 726,044.

This invention relates to new and useful improvements in an internal combustion engine, and more particularly to an engine of this character wherein the usual cam shaft 5 is eliminated in the operation of the timing of the explosion. The main object of my invention is the provision of an internal combustion engine so constructed as to eliminate the provision of the usual cam shaft, 10 which operates the timing of the engine for regulating the explosions.

Another object of the invention is the provision of an internal combustion engine of the above character which comprises comparatively few parts so as to reduce the cost 15 of production with an increase in power and speed due to an elimination of the usual drag through friction.

With the above and other objects in view, 20 the invention consists in the novel features of construction, the combination and arrangement of parts hereinafter more fully set forth, pointed out in the claims and shown in the accompanying drawings, in 25 which:

Figure 1 is a longitudinally sectional view of an engine constructed in accordance with my invention, showing the intake valve open for admitting the explosive mixture into the 30 cylinder,

Figure 2 is a similar view illustrating the position of the piston after the explosion has taken place and at the beginning of the exhaust, and

Figure 3 is a similar view showing the exhaust taking place and the piston returned prior to another explosion.

In constructing an internal combustion engine of my improved type various numbers of cylinders can be used for the purpose of illustration. I have disclosed in the accompanying drawings on one cylinder connected to the usual crank shaft 1 of means of the piston rod 2. The outer end of the piston rod 2 is connected to the piston 3 in any desirable manner, said piston being mounted for reciprocated movement within the cylinder 4.

The inner end of the piston is provided 50 with a head 5 having annular grooves within which the usual piston rings 6 are fitted for engagement with the walls of the cylinder. It will be noted that the body piston is of less diameter than the cylinder 4 leaving 55 an annular space 7 within the cylinder encircling around the piston.

Movable within the space 7 is a sleeve 8 which controls the outlet of the exhaust and disposed between one end of the sleeve 8 and the head 5 is a coil spring 9, the other end 60 of the sleeve 8 resting upon an annular flange 10 formed on the base 11 and disposed within the inner end of the cylinder 4.

The outer end of the cylinder 4 is provided with an inlet 12 through which the gaseous mixtures are admitted to the cylinder and the admission of these mixtures is controlled by means of the valve 12. Fitted 65 into the wall of cylinder 4 for the purpose of exploding the mixtures is a spark plug 14. The cylinder 4 is also provided for with an exhaust outlet 15 which is arranged at a point adjacent the inner end of the cylinder. 70

The piston 3 is provided with a centrally disposed longitudinal opening 16, the inner 75 end of which extends outwardly at right-angles as at 17 beyond the central portion of the piston to communicate with the space 7 between the walls of the cylinder and the piston for the purpose of exhausting the 80 exploded mixture.

In Figure 1 the device is illustrated prior to an explosion, the gaseous mixtures entering the open inlet 12 and accumulating within the chamber 18 between the piston head 5 and the outer end of the cylinder. As 85 the mixture is exploded, as illustrated in Figure 2, the valve 13 is forced to a closed position while the piston 3 is reciprocated toward the other end of the cylinder. 90

This movement will bring the angular end 17 of the opening 16 into registration with recess 19 formed in the flange 10 and which is disposed directly beneath the inner end 95 of the sleeve 8, thus, as the exploded mixtures pass inwardly through the opening 16, the force of the explosion will bear against the inner end of the sleeve and force the same outwardly against the compression of the spring 9, after the spring has been 100 compressed and the greater portion of the exploded mixture passed thru the opening 16 to the inner end of the piston, it will cause the tension of the spring to return the piston to its intake position as shown at

Figure 3, the sleeve 8 moving outwardly with the piston and uncovering or opening the exhaust opening 15 permitting the escape of the used gases. It will be apparent from this 110 that after the piston has reached its intake position shown in Figure 3 and the used gases are exhausted the tension of the spring

7 will return the sleeve 8 to its normal position closing the exhaust port 15 so that as soon as another explosion takes place the piston and sleeve will be in the same position prior to the previous explosion or in the position shown in Figure 1.

From the foregoing it will be apparent that I have provided a simple and efficient internal combustion engine which can be used on motor vehicles and the like and which will eliminate the usual cam shaft for controlling the timing of the engine.

While I have shown and described the preferred embodiment of my invention, it will be understood that various changes and alterations may be made without departing from the spirit of the invention or the scope of the appended claims.

Having thus described my invention, what I claim is:

1. An internal combustion engine including a cylinder having an exhaust port adjacent its inner end and an intake port adjacent its outer end, a piston movable in the cylinder and having a body portion in spaced relation with the inner walls of the cylinder and having a head portion in reciprocal engagement with the inner walls and having a passage formed therein adapted under certain conditions to communicate with the exhaust port, and a sleeve valve disposed between the body portion of the piston and the inner walls of the cylinder and movable under force of an explosion in a certain direction to open communication between the passage and the exhaust port.

2. An internal combustion engine including a cylinder having an exhaust port adjacent its inner end and an intake port adjacent its outer end, a piston movable in the cylinder and having a body portion in spaced relation with the inner walls of the cylinder and having a head portion in reciprocal engagement with the inner walls and having a passage formed therein adapted under certain conditions to communicate

with the exhaust port, a sleeve valve movable in the cylinder under force of an explosion and disposed between the body portion of the piston and the inner walls of the cylinder adapted under certain conditions to open communication between the passage and the exhaust port, and a resilient member, surrounding the body portion of the piston and disposed between the head portion thereof and an end of the sleeve valve.

3. An internal combustion engine including a cylinder having an exhaust port formed therein adjacent its inner end and an intake port formed therein adjacent its outer end, a piston movable in the cylinder and having a body portion of a diameter less than the inside diameter of the cylinder and a head portion frictionally engaging the inner walls of the cylinder and having an opening formed centrally therein with an inner end thereof adapted under certain conditions to communicate with the exhaust port, a sleeve valve disposed in the annular chamber and movable in a certain direction under force of an explosion to open communication between the passage and the exhaust port, and a coil spring between the head portion and an end of the sleeve valve adapted to resist movement of the sleeve valve in said direction.

4. An internal combustion engine including a cylinder having an exhaust port and an intake port, a piston movable in the cylinder in spaced relation with the walls thereof and having a head portion frictionally engaging said inner walls and having a passage formed therein adapted under certain conditions to communicate with the exhaust port, and means disposed in the space between the piston and inner walls movable in a direction under force of an explosion to open communication between the passage and the exhaust port.

In testimony whereof I affix my signature.

MARTIN WILLIAM LINDGREN.
